CLAIM

The ornamental design for a filter frame, as shown and described.

DESCRIPTION

FIG. 1 is a top perspective view of a filter frame of the present invention.

FIG. 2 is a top plan view of the filter frame.

FIG. 3 is a detailed top plan view of the filter frame.

FIG. 4 is a bottom plan view of the filter frame.

FIG. 5 is a detailed bottom plan view of the filter frame.

FIG. 6 is an elevation view of the front of the filter frame, the rear view being identical.

FIG. 7 is a side elevation view of the filter frame, the opposite side view being identical.

FIG. 8 is a detailed cutaway view of the side of the filter frame showing four representative ridges corresponding to the four rightmost ridges in FIG. 7.

FIG. 9 is a detailed top perspective view of the filter frame. FIGS. 10-17 are detailed top perspective views of the filter frame as the filter frame is rotated in sequence from a shallow front perspective view to a top perspective view.

FIG. 18 is a detailed front perspective view of the filter frame.

FIG. 19 is a detailed top perspective view of the filter frame; and,

FIG. 20 is a detailed top perspective view of the filter frame. The dash dot lines immediately adjacent to the claimed areas in the enlarged detail views represents the cutaway of the enlarged areas and form no part of the claimed design.
